UNITED STATES PATENT OFFICE

102,662

DESIGN FOR A VEHICLE WHEEL

Carolus L. Eksergian, Detroit, Mich., assignor to
Budd Wheel Company, Philadelphia, Pa., a cor-
poration of Pennsylvania

Application October 12, 1933, Serial No. 49,469

Term of patent 14 years

To all whom it may concern:

Be it known that I, Carolus L. Eksergian, a citizen of the United States, residing at Detroit, in the county of Wayne and State of Michigan, have invented a new, original, and ornamental Design for Vehicle Wheel, of which the following is a specification, reference being had to the accompanying drawing which forms a part hereof.

Figure 1 is a perspective view of a wheel embodying my new design.

Figure 2 is a fragmentary side elevation of the same.

Figure 3 is an axial cross section of the same.
Figure 4 is a view taken on the line 4—4 of Figure 2.

The characteristic feature of this design resides in a wheel as shown having a continuous annulus underlying the drop center portion of the rim and projecting axially outwardly so as to extend across the outer ends of the spokes.

I claim:

The ornamental design for a vehicle wheel substantially as shown and described.

CAROLUS L. EKSERGIAN.
